UNITED STATES PATENT OFFICE.

CHARLES H. SCHURR AND ERNEST J. LEES, OF CLEVELAND, OHIO, ASSIGNEES TO THE
LEES-BRADNER CO., OF CLEVELAND, OHIO.

THREAD-MILLING MACHINE.

Application filed January 12, 1918. Serial No. 211,512.

To all whom it may concern:

Be it known that we, CHARLES H. SCHURR and ERNEST J. LEES, both citizens of the United States of America, residing at 6210 Carnegie Ave., city of Cleveland, in the county of Cuyahoga and State of Ohio, have invented a new and useful Improvement in Thread-Milling Machines, of which the following is a specification, the principle of the invention being herein explained and the best mode in which we have contemplated applying that principle, so as to distinguish it from other inventions.

Our invention pertains to improvements in a thread milling machine and more particularly to changes in the relative arrangement, shape and function of certain parts which either mechanically coact with the lead screw or have some other practical indirect association therewith.

The improvements declared by this application are four in number, first, an arrangement which places the lead screw directly underneath longitudinal ways upon the bed of the machine so that such screw is sheltered and protected from above particularly against the deposit of grit and other sediment, the collection of which is attendant upon the working operation of the machine; second, the provision of an independent longer and more durable thrust bearing for the lead screw which is located between the two end bearings ordinarily till now relied upon; third, an arrangement whereby a saddle which carries the swivel head and is automatically moved by the lead screw is caused to have telescopic connection with the tail stock so that the relative longitudinal movement of the two is considerably increased; fourth, the provision of duplex means for controlling the operative connection of the lead screw and saddle, especially in the provision of means for absolutely locking the two together in addition to the frictional hold upon which reliance has heretofore been placed.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come with-

in the scope of the claims hereunto appended.

Advertising to the drawings:

Figure I is a front elevation of a thread milling machine embodying our invention with the tail stock in a certain position.

Figure II is a corresponding view showing the tail stock moved to a position somewhat nearer the head stock to exemplify its telescopic association with the saddle.

Figure III is a partial plan view of that portion of the machine which includes the telescopic arrangement of the saddle and tail stock illustrated in Figure II.

Figure IV is a vertical cross-section of the machine showing the position of the lead screw directly underneath the ways formed upon the longitudinal front.

Figure V is a right end view showing parts of the tail stock in section whereby the telescopic connection is otherwise revealed.

Figure VI is an enlarged vertical cross-section on line VI—VI of Figure I showing certain operative parts in end elevation with the swivel head removed.

Figure VII is a vertical longitudinal section on line VII—VII of Figure VI.

Figure VIII is an oblique section on line VIII—VIII of Figure VI.

The machine is supported upon a suitable bed 1 provided above with a slideway 2 along the longitudinal front of the bed. An adjacent area of the slideway is formed as an upwardly projecting guideway 3. The purpose of both ways will hereinafter appear. One end of the bed supports the head stock 4 on which a train of gearing designated entirely by the numeral 5 communicates power to a lead screw 6 which extends the entire length of the machine and is supported at opposite ends thereof in suitable bearings 7 and 8. Inasmuch as the manner of making the head stock so as to effect the harmonious rotation of the lead screw is quite common in the art and constitutes no part of this invention, the mere mention which has been made thereof is adequate. According to my invention the lead screw 6 is positioned nearer the front of the machine than has been customary and in fact is positioned closely and directly underneath the slideway 2 so that it is sheltered and thereby protected from above not only against possible impact but also kept free from the

disposition thereupon of chips, grit and sediment which would be likely eventually to injure the threads thereon. This feature while simple is a useful practical advantage and so far as our knowledge extends is new in the specific art.

The end thrust required to be reckoned within the lead screw bearings has frequently occasioned trouble, partly because of its occasional severity and partly because at the location of the bearing which I have designated by the numeral 7 insufficient space was afforded for the accommodation of an end thrust bearing large enough and strong enough to meet the needs. With this in mind we have thought to provide auxiliary end thrust bearing surfaces between the bearings 7 and 8 which are sufficiently removed in a direction toward the tail stock. The construction comprises a pair of spaced collars 9 which are pinned to the shaft 6 on opposite sides of the additional end thrust bearing 10. Brass washers 11 also appear interposed between the faced ends of the bearing and the collars.

Movable upon the guideway 3 is a saddle 12 adapted to support the swivel cutter head in conformity with the idea which constitutes the third feature of our invention. That end of the saddle 12 which is furthest from the head stock 4 is beveled off at 13. A tail stock 14 is movable upon the slide-way 2 and owing to its being hollowed at 15 is enabled to straddle the smaller end 13 of the saddle or to have what is in the nature of a telescopic fit therewith. The advantage of such an arrangement is that the tail stock may be moved considerably nearer the head stock without interference with the saddle. The two nearly extreme positions of the tail stock are indicated in Figures I and II respectively and the manner in which the tail stock is intersected by the reduced extremity of the saddle will be further evidenced upon inspection of Figures III and V. The movement of the tail stock may be accomplished in the ordinary way by turning a hand wheel 16 which in turn rotates a pinion 17 in engagement with a rack 18 which is carried along the front of the machine.

In machines of this character it is desired frequently to reverse the cutter head independently of the automatic drive or longitudinal traverse movement thereof by means of the lead screw. To this end it has been common in the art to loosen certain parts so as to enable idle movement of the supporting saddle irrespective of any movement on the part of the lead screw. Till now, so far as our knowledge extends, this was accomplished by the loosening of a frictional hold which obtained during the automatic working traverse as between the lead screw and a coacting internally threaded

sleeve carried by the saddle. We have discovered that such frictional hold was necessarily coarse and insufficiently reliable where absolute precision was desirable or necessary and accordingly have provided an additional firmer connection between the lead screw and sleeve which would absolutely lock the parts in some predetermined relative position. Ordinarily the absolute lock connection between the sleeve 19 and saddle 12 is employed. There are occasions, however, when such an absolute lock does not permit of an adjustment of sufficient delicacy and it is at such times that frictional engagement is relied upon and as it happens at such times also the frictional engagement is sufficient because the cutting engagement is less severe when the frictional engagement is to be relied upon. Suppose a piece to have been cut, taken out and found not small enough, necessitating that it be placed back on the machine for recutting. No identification marks being on the shaft the relation of the threads to the position of the cutter is not correctly ascertainable. The precise position of the cutter is not known. In such a case the positive or lock connection is released and the nut rotated so as to move the cutter lengthwise of the bed and then after it is properly located the frictional hold will answer satisfactorily because the subsequent finishing cut is comparatively fine.

Rotatably mounted in a hanger depending from the saddle 12 is an internally threaded sleeve 19 adapted to cooperate with the lead screw 6. This sleeve is flanged at one end at 20 and such flange carries on one side a beveled gear 21 and on the other side an auxiliary sleeve 22 the fixed relation being effected by means of pins 23. The auxiliary sleeve 22 is provided with circumferential notches 24 seen in Figures VI and VIII, the purpose of which will hereinafter become apparent. In screw threaded connection with a boss 25, formed on the under side of the hanger, is an adjustable nut having the outer end of its stem provided with a handle 26, the inner end of which is adapted to engage a clamping shoe 27 disposed in a suitable slot 28 and movable into and out of an annular groove 29 fashioned in the sleeve 19. By this arrangement the clamping shoe 27 may be caused frictionally to engage the sleeve to prevent its rotation and therefore to cause its axial movement whenever the lead screw 6 turns. A thumb screw 30 passes through a projection 31 on the hanger in such a manner that the inner extremity 32 of the screw may be entered into any one of the circumferential notches 24 and thereby the additional or lock connection effected between the sleeve 19 and the saddle 12. The usual hand wheel 33 upon the outer end of the shaft 34 serves to rotate the latter and therefore a bevel pinion 35 which is carried on

the opposite end of the shaft in mesh with the beveled gear 21. This is the usual contrivance by means of which, after the sleeve 19 is loosened, it may be rotated about the 5 screw so as to accomplish the return of the saddle in a direction toward the tail stock.

The arrangement according to which the lead screw is disposed directly underneath the guideway 3 of the saddle 12 eases and 10 perfects the action which determines the lead because the thrust therealong is more nearly parallel owing to the fact that the lead screw is in the same vertical plane as the center line of the saddle. In this way 15 accessibility, durability and accuracy are had. Less friction is encountered where the guideway and slideway are brought close together particularly when superposed as we have disclosed than if they were separated 20 so that one was along the front of the machine and the other along the back thereof.

We claim:

1. A thread milling machine comprising a bed formed with ways, work and tool 25 holders thereon, a saddle supporting one of said holders and movable upon said ways, driving means, a lead screw operatively connecting said driving means with said saddle, friction means for controlling said connection and distinct means adapted to lock said connection.

2. A thread milling machine comprising a bed formed with ways, work and tool holders thereon, a saddle supporting said tool holder and movable upon said ways, an internally threaded sleeve mounted in said saddle, driving means, a lead screw cooperating with said sleeve and operatively connected with said driving means to effect the automatic traverse of said saddle, and a locking device including parts carried by said saddle and sleeve respectively to secure the same together. 35

3. A thread milling machine comprising a bed formed with ways, work and tool holders thereon, a saddle supporting said tool holder and movable upon said ways, an internally threaded sleeve rotatably mounted in said saddle and fashioned with circularly arranged notches, driving means, a 45 lead screw cooperating with said sleeve and operatively connected with said driving means to effect the automatic traverse of said saddle, means for frictionally binding said sleeve and saddle together, and means carried 50 by said saddle and adapted to project into one of said notches whereby absolutely to lock said sleeve and saddle together. 55

Signed by us, this 28th day of December, 1917.

CHARLES H. SCHURR.
ERNEST J. LEES.
